UNITED STATES PATENT OFFICE.

FRANK AMOS JOHNSON, OF DUNELLEN, NEW JERSEY, ASSIGNOR TO SIGNATURE COMPANY, OF NEW YORK, N. Y., A CORPORATION OF NEW YORK.

PEN-CLAMP FOR MULTIPLE-WRITING MACHINES.

1,073,240.

Specification of Letters Patent. Patented Sept. 16, 1913.

Application filed September 5, 1912. Serial No. 718,642.

To all whom it may concern:

Be it known that I, FRANK AMOS JOHNSON, a citizen of the United States, and a resident of Dunellen, in the county of Middlesex and State of New Jersey, have invented a new and useful Pen-Clamp for Multiple-Writing Machines, of which the following is a specification.

My invention relates to machines for simultaneously writing a plurality of signatures and to that particular class of these machines in which the pens or writing members are rigidly secured to the pen-bar.

In order to produce uniformity in the signatures it is necessary that all the pens should strike the writing surface at exactly the same time.

The object of my invention is to provide a pen-clamp which can be readily adjusted to and from the writing surface; which can be quickly adjusted on the pen-bar in any desired position; which can be easily removed from the pen-bar and from which the pen may be easily and quickly removed.

Reference is made to the accompanying sheet of drawings.

Figure 1 is a side elevation of the pen-clamp, showing a pen in position and a small portion of a pen-bar; Fig. 2 is a front elevation the pen bar being shown in section; Fig. 3 is a side elevation of a pen-bar and its guide handle—one pen being shown in position and the position of others being indicated; Fig. 4 is a sectional side elevation on line X—X of Fig. 2; and Fig. 5 is a modified form of the pen-clamp a portion of the pen bar showing in section.

The pen-bar B is T-shaped and has secured to it a pair of hinge blocks 1, by means of which it is pivotally connected to a pair of arms 2. Only a portion of the arms are shown and the manner in which the arms are mounted is not illustrated, as that has no bearing on my present invention. The pen-bar is provided on its upper side with a longitudinal slot 3. The pen-clamp C is formed with a horizontal portion 4 and an oblique portion 5. In this latter portion the pens P are secured by clamp screws 6. Each pen is provided with a band or collar 7 which consists of a spring ring. The joint of the ring 7^a is made to aline with a slot 8 of the portion 5 of the pen-clamps when the pens are in right position. On loosening the clamp

screw 6 the pen may be readily removed from the clamp and it can be quickly put back in place by inserting the pen as far as the band 7 will permit and by turning the pen until the slots 7^a and 8 are in line.

The horizontal portions 4 of the pen clamps have flanges 4^a which extend over the top of the pen-bar. In these flanges, near their front ends, are set screws 9 and near the rear ends there are knurled adjusting screws 10. All these screws bear against the pen-bar in its slot 3. Directly under the set screws 9, on the under side of the pen-bar, each clamp has a pin or stud 11 which carries a spring 12, the rear end of which is adapted to bear against the pen-bar directly opposite the adjusting screws 10. From this construction it can be seen that the front end of the pen-clamp is pivoted to the pen-bar on a horizontal axis and that as the adjusting screws 10 are turned the pen points P' will move in the arc a to or from the platen or writing surface W. The pen points being flexible, the springs 12 are made stiff enough so that the pressure which is applied to the pen points in shading will not cause them to yield. When once set the pen clamps are, for all practical purposes, quite rigid.

In Fig. 3 I have shown one pen attached to the pen-bar and have indicated by lines P^a the position of four other pens. When it is desirable to change this spacing the pen clamps are readily moved along on the pen-bar in either direction—the springs 12 being sufficiently strong to hold them in position. The set screws 9 may, however, be set up tight enough to prevent the clamps being moved and still not interfere with the rocking action of the pen-clamps as the adjusting screws 10 are turned.

Various modifications of the construction just described may be made. One form is shown in Fig. 5, where a lug 13 is substituted for the set screw 9.

It will be evident that with either form of clamp herein described, that they may be placed on the pen-bar in any desired position and that they may be easily removed from the bar by sliding to either end.

My improved construction of pen-clamp permits the quick setting up of the writing machine with any desired number of pens, in any desired position on the pen-bar and the pens can be quickly adjusted to the

writing surface and held in an effective manner.

What I claim is:

1. In a machine of the class referred to, a pen-bar; a plurality of pen-clamps mounted thereon—said pen-clamps being each adapted to hold a writing member—one end of each of said pen-clamps having a pivotal axis on said pen-bar; in combination with means for adjusting the opposite or free end of said pen-clamps in a vertical direction to and from said pen-bar.

2. In a machine of the class referred to, a pen-bar; a plurality of pen-clamps mounted thereon—one end of each of said pen-clamps engaging said pen-bar on its upper and under side to form a horizontal axis for said pen-clamps; in combination with means for adjusting the other or free end of said pen-clamps in a vertical direction to and from said pen-bar.

3. In a machine of the class referred to, a pen-bar; a plurality of pen-clamps mounted thereon—one end of each of said pen-clamps having a horizontal pivotal axis on said pen-bar; in combination with a spring attached to each of said pen-clamps and adapted to draw the outer or free ends of said pen-clamps downward toward said pen-bar and adjusting screws in the outer or free ends of said pen-clamps for adjusting said free ends to and from said pen-bar.

4. In a machine of the class referred to, a pen-bar having a longitudinal slot; a plurality of pen-clamps mounted on said pen-bar—one end of each of said pen-clamps being provided with a projection on one side of said pen-bar and a set screw on the opposite side of said pen-bar—said set

screw being adapted to enter the slot in said pen-bar—said projections and said set screws engaging said pen-bar to form horizontal pivotal axes for said pen-clamps; in combination with a spring on each of said pen-clamps which springs are adapted to draw the free end of said pen-clamps toward said pen-bar and an adjusting screw in the free ends of said pen-clamps which screws are adapted to enter the longitudinal slot of said pen-bar.

5. In a machine of the class referred to, a pen-bar; a plurality of pen-clamps mounted thereon, each adapted to be rocked on a horizontal axis with relation to said pen-bar and to be moved longitudinally on said pen-bar; in combination with a spring on each of said pen-clamps which is adapted to rock said pen-clamps with relation to said pen-bar and means for rocking said pen-clamps against the tension of said springs—said springs serving the additional office of holding said pen-clamps in their longitudinal position on said pen-bar.

6. In a machine of the class referred to, a pen-bar; a pen-clamp having a pivotal axis slidable with relation to said pen-bar and adapted to hold a writing member; in combination with means for rocking said pen-clamp on its axis with relation to said pen-bar, whereby the pen may be adjustably secured in its position on the pen-bar and in relation to the writing surface.

In testimony whereof I affix my signature in presence of two witnesses.

F. AMOS JOHNSON.
